UNITED STATES PATENT OFFICE.

FREDERICK C. OVERTURB, OF HILLSDALE, NEW JERSEY, ASSIGNEE, BY MESNE ASSIGNMENTS, TO THE FLINTKOTE COMPANY, OF BOSTON, MASSACHUSETTS, A CORPORATION OF MASSACHUSETTS.

PROCESS AND APPARATUS FOR MAKING ROOFING ELEMENTS.

1,286,077.

Specification of Letters Patent.

Patented Nov. 26, 1918.

Application filed March 15, 1917. Serial No. 154,935.

To all whom it may concern:

Be it known that I, FREDERICK C. OVERTURB, a citizen of the United States, residing at Hillsdale, in the county of Bergen and State of New Jersey, have invented new and useful Improvements in Processes and Apparatus for Making Roofing Elements, of which the following is a specification.

The instrumentalities for manufacturing prepared roofing are necessarily large and occupy much space in the factory, and are expensive not only as to first cost but also as to their cost of maintenance and operation.

The object of the present invention is an increased production of roofing material at a relatively much lower cost, without duplicating the instrumentalities required for coating and mineral-surfacing the sheet roofing.

In accordance with the present practice, a sheet of fibrous material is first saturated or impregnated with a waterproofing compound consisting of asphalt or other hydrocarbon or bituminous material, after which it is coated on one face with a layer of high-melting-point pitch or asphalt, and, while the coating is relatively soft and plastic, a facing of grit or crushed slate or other mineral is applied thereto and partially embedded therein. The sheet thus coated and mineral-surfaced is cut into shingles or strips as may be desired. During its passage from the impregnating vat or kettle to the cutting machine, the sheet is subjected to the treatment of cooling or chilling instrumentalities. The speed at which the sheet may be fed through the various instrumentalities is necessarily limited as is well known by those skilled in the art, and in consequence a point is soon reached in which with a given set of instrumentalities the production cannot be increased without the installation of a duplicate set of machinery with the consequent increase in expense.

In accordance with my invention, I am able to increase the production of mineral-surfaced sheet roofing without increasing the instrumentalities, and with merely the addition of a cutting machine in case the roofing is to be marketed in the form of shingles or strips. I do this by passing two separate and unattached sheets of fabric in facial engagement simultaneously through

the single set of instrumentalities and then separately packaging or otherwise treating the sheets for final use. In this way I double the output of the apparatus with practically no increase in expense except as may result from the use of the raw materials, or from finally cutting the sheets into shingle or strip form.

On the accompanying drawing, I have in Figure 1 conventionally illustrated the instrumentalities for simultaneously coating, surfacing and cooling two independent and separate sheets together with the machines for cutting the sheets into shingle strips.

Fig. 2 conventionally shows a vat in which two independent sheets of felt may be simultaneously saturated or impregnated.

Referring to the drawings, I have illustrated in Fig. 1, at 5, 5, two rolls of felt which have been previously impregnated with a waterproofing compound such as herein described, and from which the two sheets 51, 52, are drawn into facial contacts by draw rolls 6, 6, of any suitable form or design, which also act to coat the outer faces of the two sheets with molten high-melting-point pitch or asphalt. After being brought into contact, the two sheets are fed synchronously through the remaining instrumentalities. To prevent the sheets from adhering, talc, soapstone, or other equivalent material, may be fed by any suitable means on the upper horizontal surface of the sheet 52 before the sheets meet under pressure of the rolls 6. From the coating rolls the sheets are caused to pass through the machine by which the crushed mineral is spread upon and partially embedded in the plastic coating. The sheets first pass beneath the distributing trough 7, from which the crushed mineral is deposited in a layer upon the coating on the sheet 51, and then around the roll 8 by which the mineral is pressed or partially embedded in the said coating. The two sheets thence pass to the roll 9 and during their passage crushed slate or grit is spread upon the still plastic coating on the sheet 52 from the trough 10. The sheets pass up and over the roll 9, so that the last-mentioned layer of grit is partially embedded in the coating on sheet 52. The batches of grit in the two troughs may be

2
different or the same in color as desired and may be supplied thereto through conduits 12, 13, leading from overhead receptacles (not shown). After leaving the surfacing 5 machine the two sheets pass through a series of pairs of cooling drums 15 through which water or other cooling medium is circulated, following which the sheets pass through a festooning mechanism conventionally indicated at 16 for further cooling. At the ends 10 of the festooning mechanism are the two pairs of draw rolls 17, 18, which feed the two sheets in synchronism. Up to this point, the sheets remain in facial contact and 15 move at the same speed through the various instrumentalities, but from the draw or feed rolls 18 the sheets are passed in divergent paths. If the sheets are to be packaged and shipped in roll form, they are passed to 20 separate winding mechanisms; but, as they may be cut into strips or shingles, I have illustrated the sheets as being passed to the two separate machines 20, 21, arranged at different elevations. Any suitable shingle- 25 or strip-cutting machines may be utilized for the purpose, and it is not necessary to describe them in detail. For example, I may employ machines substantially as illustrated in my Letters Patent Nos. 1,182,416 and 30 1,182,417, dated May 9, 1916.

In Fig. 2 of the drawing I have shown how two sheets of felt may simultaneously be impregnated in the same tank, the mechanism shown being of course conventional or 35 more or less diagrammatic. The two felt sheets 51, 52, are drawn from the rolls 30, 31, and, after passing through the bituminous or hydrocarbon compound in the tank 32 (in which the compound is main- 40 tained in a molten condition by any suitable heating apparatus), are subjected to the action of the squeeze rolls 33, 34, by which the surplus compound is pressed from the sheets. I have not deemed it necessary to 45 illustrate the cooling drums and festooning mechanism which would be interposed between the compound tank and the coating rolls 66, in case the sheets be passed directly from the tank to the coating rolls, but it 50 will be understood that the sheets are brought into facial contact on reaching the cooling drums. The sheets may be facially separated after being cooled and before being passed to the coating rolls 6, 6, to permit 55 of the application of talc, soapstone or the like to the inner faces of the sheet to allow the necessary relative slippage of the sheets as they travel through their tortuous path to the cutting machines. In 60 case of any tendency to adhere at their edges after being subjected to the action of the coating rolls caused by the creeping of the coating between the edges of the contacting sheets, I may employ separator blades to 65 enter between said edges and spouts for de-

positing lines of talc or soapstone between the said edges or marginal portions of the sheets.

I am aware that frequently it has been proposed to feed two sheets into contact as 70 in the manufacture of multiple-ply roofing, but in all of the cases of which I have knowledge such sheets were permanently united by cementitious matter into a single composite sheet, and I believe that I am the first to perform the operations described in the foregoing specification and pointed out in the claims, by which two separate and distinct coated, or coated and mineral-surfaced sheets are produced simultaneously by a 80 single set of mechanisms. Aside from saving floor space and labor, I am able to simplify the piping for the cooling medium and effect a material saving in that respect. 75

Having thus explained the nature of my 85 invention and described both a process and instrumentalities for practising the same, without attempting to describe all of the processes and different forms of instrumentalities which may be followed or employed, 90 what I claim is:

1. The herein described process of manufacturing flexible roofing material which consists in bringing into facial relation two 95 separate sheets of fibrous material impregnated with a waterproofing compound, coating the exterior faces of said sheets with a bituminous compound, spreading crushed mineral material on the coats of compound and partially embedding said crushed mineral therein, and then separating said sheets for further treatment or manipulation, the coating and surfacing operations taking place while the inner faces of said sheets are in facial or confronting relation. 100

2. The herein described process of making flexible roofing material which consists in bringing into facial contact two sheets of fibrous material impregnated with a hydrocarbon waterproofing compound, simultaneously coating the outer faces of said sheets with a bituminous compound, spreading and partially embedding crushed mineral in one of said coated sheets, then spreading and partially embedding crushed mineral in the other of said coated sheets and simultaneously cooling said sheets, all while in facial contact, and then separating said sheets for further treatment or manipulation. 115

3. The herein described process of making 120 flexible roofing material which consists in bringing into facial contact two sheets of fibrous material impregnated with a hydrocarbon waterproofing compound, simultaneously coating the outer faces of said sheets with a bituminous compound, spreading and partially embedding crushed mineral in one of said coated sheets, then spreading and partially embedding crushed mineral in the other of said coated sheets and simultane- 125 130

ously cooling said sheets, all while in facial contact, then separating said sheets, and finally simultaneously dividing said sheets into a plurality of roofing elements.

5 4. The herein described process of making flexible roofing material, as set forth in claim 1, in which the separate sheets of impregnated fibrous material are simultaneously impregnated while out of facial contact and subsequently cooled preliminary to being coated.

10 5. A process as described in claim 1, in which a layer of finely divided material for preventing adherence of the sheets when brought into facial relation is fed between the sheets prior to their being coated on their outer faces.

15 6. The combination with a machine having means for applying a waterproof coating compound on the exterior faces of fibrous material, and a machine having means for applying and partially embedding a surface

layer of crushed mineral material in said coated faces, of means for feeding separate sheets of said fibrous material while in confronting facial relation to said machines to cause the outer faces only of said sheets to be coated and then surfaced, and means for separating said sheets for further manipulation or treatment.

25 7. The instrumentalities combined as in claim 6, in combination with mechanism for simultaneously cooling said sheets after being coated and surfaced, and before being separated.

30 8. The instrumentalities combined as in claims 6 and 7, in combination with machines for automatically and simultaneously cutting said sheets into a plurality of roofing elements.

35 40 In testimony whereof I have affixed my signature.

FREDERICK C. OVERBURY.
